HAIRDRESSER'S BASIN

Ralph Barrow, Tyler, Tex.

Application March 21, 1949, Serial No. 1,503

Term of patent 3½ years

(CL. D86—10)

To all whom it may concern:

Be it known that I, Ralph Barrow, citizen of the United States of America, residing at Tyler, in the county of Smith and State of Texas, have invented a new, original, and ornamental Design for a Hairdresser's Basin, of which the following is a specification, reference being had to the accompanying drawing, forming part thereof.

I claim:

The ornamental design for a hairdresser's basin, substantially as shown.

RALPH BARROW.
